JOHN B. DOWNING, OF ORANGE, NEW JERSEY, ASSIGNOR TO BEAVER MACHINE AND
TOOL CO., INC., OF NEWARK, NEW JERSEY

CONNECTER

Application filed July 9, 1926. Serial No. 121,373.

The object of my invention is to provide a separable means for attaching a cable consisting of a plurality of wires which form a plurality of electric circuits to a translating device, in a manner that precludes the possibility of accidentally connecting the wrong circuits together.

A further object is to provide a housing to encase the wires at the point of juncture and interlock them in a predetermined relative position.

A further object is to provide a cable connector which is simple, economical to manufacture, and to which the various wires comprising the cable may be attached in a safe and secure manner.

Attention is directed to the drawings which illustrate the preferred form of my invention in which:

20 Figure 1 is a cross sectional elevation thru the plug taken on line 1-1 of Figure 2.

Figure 2 is a plan view of the connector.

Figure 3 is a cross section thru the connector taken at right angles to Figure 1, as 25 along line 2, Figure 2, and shows one half of the plug only, it being understood that the other half is of the same construction.

Figure 4 is a section thru the cap member.

30 Figure 5 is a plan of the cap member.

Figure 6 is a plan of an insulating spacing disc.

Figure 7 is a section thru the body member.

35 Figure 8 is a plan of the body member.

Figure 9 is a plan of the plug member.

Figure 10 is an elevation, partly in section of the plug member.

40 Figure 11 is an edge elevation of the female contact member.

Figure 12 is a side elevation of the female contact member.

45 Figure 13 is an edge elevation of the male contact member.

Figure 14 is a side elevation of the male contact member.

To the end that the objects stated may be attained I employ a cap member 1 which is dome shaped and is provided with a central hole 2 for the reception of a cable. I also employ a body or barrel like member 3, which houses a set of cable terminals. I employ a plug section 4 which also carries a set of cable terminals. The plug member, body member and cap member, are made from any suitable moulded insulation as for example, phenolic compounds, etc.

The plug section 4 is rigidly attached to the translating device by a bracket 5 or 60 equivalent means.

Its purpose is to provide a carrying means for male contact members 6.

Referring to Figures 13-14 which show the male contact members 6 in detail, 7 is a terminal section for attaching an end of a cable wire to, 8 is a contact section; adjacent the end of the contact section 8 is a raised section 9, preferably semi-circular in form which co-acts with a like raised section 9^a in the female contacts 10. The terminal section 7 is bent at an obtuse angle to the contact section 8. A boss 11 is coined in the contact section 8 and terminates at the bend which forms the terminal section 7. Approximately midway between the end of the terminal section 7 and the bend a hump like bend 12 is made, the purpose of which will be explained later on.

75 Referring to Figures 9-10 which show the plug member in detail 13 is a body portion and 14 is a flange portion.

The body portion 13 has a central hole 15 for a mounting screw 16, terminating in a hexagonal pocket 17 for holding a mounting nut 18. The periphery is divided by key ways slots 19-19, etc. which run from the end, thru the flange portion 14. Located in radial alignment with the slots 19-19, etc., and starting midway between the outer sides 85 90

of the slots in the flange 14 and terminating at the outer edge of the flange 14 are depressions 20. The flange 14 is provided with eyelet holes 21-21 which are countersunk as at 22-22 for eyelet flanges.

In assembling the contacts 6, to the plug 4, the contact section 8 is passed thru the key slots 19 until the portion midway between the bend and the hump 12 rests against the outside of the flange. After all of the contacts 6 are in their respective slots an insulating disc 24 is placed over them and made fast to the flange 14 by the eyelets 24*. As the male contact is formed with an obtuse angle, the point or end adjacent the raised portion 9 is pressed tightly against the bottom of the slots 19 by the pressure of the insulating disc 23 bearing on the terminal portion 7 of the contact. This same pressure forces the humped bend 12 into the depression 20. The hump and depression now contact to prevent any tendency of the contact to get out of alignment.

The coined boss 11 acts as a space filler to take up the excess space in the key slot 19 which is relatively much greater than the cross section of the metal forming the spring contact 6. The boss also holds the contact in the correct relationship with the bottom 30 of the slot in which the end adjacent the raised portion 9 presses against.

Referring to Figures 7-8 which show in detail the construction of the body or barrel member 3, 25-25, etc., are internal key-way slots for the reception of female terminals 10. A registering slot 27 interlocks with a registering key 28 on the plug member 4. These registering elements are provided so that the body 3 may be fitted to the plug 4 in one relative position only. Inserts or eyelets 29 are moulded in one end of the body portion and are tapped for the reception of a screw as will be explained later on. On the outer periphery an index boss 30 is formed in radial alignment with the key slot 27. The purpose is to indicate readily the position of the key slot 27 when the parts are about to be joined together.

Female contacts 10 are provided with a straight base portion 31, a foot portion 32 and a resilient portion 33 which is bent at an acute angle to the base portion 31. Holes 34 are placed in the end of the resilient portion to provide means for easily soldering lead wires to the terminal.

An insulating disc 23 is pierced with holes 35-35 etc. These holes are in alignment with slots 19 of the plug member 4 and slots 25 of the body member 3. Slots 36 radiate from either side of the holes 35, etc., and form an aperture for the passage of the resilient end 33 of the contact 10.

Two rivet holes 37-37 are spaced diametrically opposite each other and are of

such size as to readily fit over inserts 29 in the body section 3.

The cap member 1, is provided with holes 38-38 also in register with inserts 29. In order to have as much room as possible to house the ends of the cable wires the inside of the cap is relatively large and has bosses 39-39 to form a wall around one side of the holes 38-38.

So as to obtain a neat appearance the cap is cut out as at 40-40 (Figures 2-3) to form shelves for the heads of the screws 41-41 to rest on when assembled.

To form a unitary structure of the body or barrel member 3, the contacts 10 are placed in the slots 25 until the foot member 32 rests on the end of the barrel, this leaves the extreme ends of the resilient members 33 projecting out of the barrel for a distance. The insulator disc 23 is fitted over the resilient members 33 and the inserts 29 which are then spun or riveted over to hold the disc in place.

Referring to Figure 1 it will be evident that the assembled barrel and contacts will fit over the assembled plug and contacts so that the semi-circular raised section 9 on the male contact 6 matches within a like section 9* on the female contacts 10 and as the contacts 10 are resilient the parts will fit together with a snap action.

The cap member 1 is to be slipped over the cable (not shown) before attaching the lead wires of the cable to the contacts 10 at the holes 34. After the attachment is made the cap member is pushed over the cable until it rests on the insulator 23, the screws 41 are then passed thru the holes 38 of the cap and threaded into the inserts 29.

This cable end is then entirely housed within and protected by the cap 1, insulator 23 and barrel 3 and is attached to the live ends of the circuits.

The plug member may be considered as a distributing block and is housed within the translating device (not shown).

While I have shown and described the preferred form of my invention it will be understood that various forms and modifications are possible without departing from the spirit of the invention and I do not limit myself to the exact structures shown.

Having described my invention, I claim:

In a connector for a multi-circuit cable, a plug member of insulating material provided with grooves parallel to its longitudinal axis and having a flange at one end, said flange being provided with holes registering with said grooves; contact members having a major portion extending thru said holes and grooves and having a minor portion lying against the outer face of said flange, a body member of insulating material surrounding said plug member and having grooves parallel to its longitudinal axis;

contacts each having a flat portion to rest against one end of said body member, a section at right angles to said flat portion extending within one of said grooves and a resilient section bent back parallel to said flat portion in contact with one of said first named contacts and extending relatively farther back from said end of said body; and a cap member for housing said end.

5 10 Signed at Newark, N. J., this 7th day of July 1926.

JOHN B. DOWNING.
